(57) **CLAIM**

The ornamental design for a fidget toy, as shown and described.

DESCRIPTION

FIG. 1 is a perspective view of a fidget toy showing the design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an exploded view of the fidget toy.

The broken lines in the reproductions depict portions of the

fidget toy that form no part of the claimed design.

1 Claim, 9 Drawing Sheets
